Friedrich LLP

(57) **CLAIM**

The ornamental design for a camera, as shown and
described.

DESCRIPTION

FIG. 1 is a top, front and right side perspective view of a
camera showing our new design;

FIG. 2 is a top, rear and right side perspective view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a top plan view thereof.

The broken lines depict portions of the camera in which the
design is embodied that form no part of the claimed design.

1 Claim, 5 Drawing Sheets

Related U.S. Application Data

a continuation-in-part of application No. 29/437,112, filed on Nov. 13, 2012, now Pat. No. Des. 775,255, and a continuation-in-part of application No. 29/446, 359, filed on Feb. 22, 2013, now Pat. No. Des. 726,238.
